UNITED STATES PATENT OFFICE.

GEORGE MERCHANT, JR., OF GLOUCESTER, MASSACHUSETTS.

PURSE-BLOCK FOR SEINES.

SPECIFICATION forming part of Letters Patent No. 288,650, dated November 20, 1883.

Application filed July 7, 1882. (No model.)

To all whom it may concern:

Be it known that I, GEORGE MERCHANT, Jr., of Gloucester, in the county of Essex and State of Massachusetts, have invented a new 5 and Improved Purse-Block for Seines, of which the following is a specification.

This invention has for its object the substitution, for the ordinary purse-ring used in seines, (a plain iron ring,) of a pulley-block 10 adapted especially for use in "pursing" the seine, and having provision for the "purse-rope" and "bridle-rope."

In the accompanying drawings, in which similar letters of reference indicate like parts, 15 Figure 1 is a view of a seine, showing the position of the purse-blocks. Fig. 2 is a view of my improved purse-block. Fig. 3 is a vertical longitudinal section of the same.

In Fig. 1, A represents the seine; B, the 20 corks on top of it; C, the bridle-ropes; D, the purse-blocks; E, the purse-rope.

As formerly constructed, common iron rings are placed where the blocks D are in Fig. 1, 25 the bridle-ropes C are fastened to these rings, connecting with the seine, and the purse-rope E passes through said rings and into the boat at X. To raise the seine and remove the fish, the purse-rope E is drawn into the boat, pursing up the seine, and slipping through the 30 rings. Much friction is necessarily caused by this process, and consequently much strength required. It is to relieve this friction that I have produced the pulley-blocks D. (Shown enlarged in Figs. 2 and 3.) The purse-rope 35 E passes over the pulley G in the shell D', and

the bridle-rope passes under the cross-bar H, (through the opening I above the partition J,) and is made fast to said cross-bar by means of a cord, K, to accommodate which a gouge or depression, L, is made therein. When the 40 seine is pursed up, the pulley-blocks, being brought close together, are in danger oflapping into each other—*i. e.*, the shells D' are apt to be forced in upon the pulleys G in the next blocks and interfere with the pulleys and 45 rope E. To prevent this, I have provided the fenders S, one on each edge of the shell, as shown, so that there is no danger of the blocks interlocking or catching into each other. Thus a practical block is constructed for use in 50 seines, and great friction is avoided.

Having thus fully described my invention, what I claim, and desire to secure by Letters Patent, is—

The herein-described purse-block for seines, 55 consisting of the shell D', provided with the fenders S, extending laterally across the same, on opposite sides thereof, the horizontal partition J above the pulley G, and the cross-piece H, located at the upper end of the frame, 60 and provided with an indentation for the reception of the cord, by means of which the bridle-rope is secured, all combined and arranged substantially as and for the purpose set forth.

GEO. MERCHANT, JR.
